Primary Examiner — Paula Greene(74) *Attorney, Agent, or Firm* — Young & Thompson(57) **CLAIM**

The ornamental design for a headset, as shown and described.

DESCRIPTION

FIG. 1 is a front, left side perspective view of a headset showing the new design;

FIG. 2 is a left side elevation view thereof, with the opposite side being identical;

FIG. 3 is a front elevation view thereof; and,

FIG. 4 is a rear elevation view thereof.

The portions of the design shown in broken lines show unclaimed subject matter.
